UNITED STATES PATENT OFFICE.

ERNEST J. ALLEN, OF ELMHURST, NEW YORK.

DRILL-SLOTTER.

1,367,680.

Specification of Letters Patent.

Patented Feb. 8, 1921.

Application filed November 8, 1919. Serial No. 336,660.

To all whom it may concern:

Be it known that I, ERNEST J. ALLEN, a subject of the King of Great Britain, and resident of Elmhurst, Long Island, in the 5 county of Queens and State of New York, have invented certain new and useful Improvements in Drill-Slotters, of which the following is a specification.

This invention relates to improvements in 10 machines for performing slotting or other similar machining operations. The main object of the invention is to so design and construct the necessary parts that the entire device may be applied to the table of an 15 ordinary drilling machine and be driven by the drill spindle with the ordinary drill socket. My invention, in its preferred form, embodies an inexpensive attachment for a drilling machine whereby simple slotting or 20 other similar operations may be performed thus obviating the necessity of having an entirely separate and expensive machine for this purpose. A further object of my invention is to provide a substantial and 25 rugged design adapted to furnish a wide range of speeds and suitable for various classes of work, but which can be manufactured and sold at a very small part of the price ordinarily charged for machines de- 30 signed to accomplish the same work. My improved device is sufficiently light to permit of its being readily lifted on to or off the drill table and is so constructed as to permit of its being rigidly secured in place 35 or detached in a very few minutes. The device may be used for cutting key-ways, straight or at an angle, slotting rectangular holes, profiling, cutting clearance on dies, filing and many other similar small jobs of 40 this class which ordinarily require the use of a large machine.

In the accompanying drawings I have 45 illustrated one embodiment of my invention although it will be evident that various other forms may be readily designed within the scope of my invention and various changes in detail and arrangement of parts may be made within the spirit thereof.

In these drawings:

50 Figure 1 is a side elevation, certain of the parts being shown in a central vertical section;

Fig. 2 is a face view of the eccentric driver;

Fig. 3 is a top plan view of the head portion; and

Fig. 4 is a front elevation.

In the specific form illustrated the machine includes a base 10 adapted to be rigidly bolted to the table of a drill press 60 or to any other suitable support. This base has an upwardly extending standard for supporting the operating parts. This standard may, in some constructions, be of a single piece, but where adjustment is desired, 65 it may be made of separate sections adjustably secured together to permit a raising or lowering of the operating parts. Merely for purpose of illustration, I have shown the base provided with an upwardly extending standard section 11 integral therewith to which is bolted an upper section 12, there being a plurality of bolt holes whereby the parts may be secured together with the upper end of the standard 12 at different elevations above the base 10. The upper end 70 of the standard is shown as providing a bearing 13 for a substantially horizontal shaft 14 and a bearing 15 for a substantially vertical shaft 16. These two shafts are connected by suitable gearing, for instance, 75 miter gears 17 and 18, to drive the shaft 14 at the desired speed.

The upper end of the shaft 16 is so constructed that it may fit into the ordinary 85 drill socket on a drill press and the shaft be rotated with the drill socket in place of the ordinary drill. This upper end portion of the shaft may thus be varied in accordance with the shape, size and kind of the drill 90 socket with which the machine is to be used. A forwardly extending arm portion 19 on the standard has a vertical guideway within which the tool carrier 20 may reciprocate. This tool carrier is shown as having opposite 95 side bevel side faces engaging with corresponding flanges 21 and 22 at the front end of the arm 19, one of these flanges, for instance 22, being adjustable and removable to provide the desired clearance and for 100 easy assembly. The center line of the tool carrier 20 preferably intersects a projection of the axis of the shaft 14, and the guide portion is supported by side members spaced to form a chamber or aperture in the rear 105 of the guide. Within the chamber are mounted the gears 17 and 18 and suitable driving connections between the shaft 14

and the tool carrier. The driving connections are illustrated as including a pitman 23 journaled on a bolt 24 rigidly secured to the upper end of the tool carrier. Preferably the bolt 24 is mounted in a slot 25 so that the tool carrier may be raised or lowered in respect to the limiting positions of the pitman. The lower end of the pitman has eccentric connections to the shaft 14. 10 To provide for varying the length of stroke of the tool carrier, the outer surface of the miter gear 18 has a radially extending flange 26 provided with a slot 27 within which a crank pin 28 may be rigidly secured. This 15 pin may be adjusted lengthwise of the slot so as to vary the diameter of the circle in which it travels thereby varying the stroke of the tool carrier.

The tool may be secured to the lower end 20 of the tool carrier in various ways, but preferably so as to permit of a rotary adjustment of the tool about its axis. The tool is shown as having a cylindrical shank 29 projecting into a chamber or cavity 30 in 25 the lower end of the tool carrier. A simple and efficient way of rigidly connecting the two includes the use of a pair of U bolts encircling the tool 29 and having their ends projecting through the front wall 32 of the 30 tool carrier and provided with suitable retaining nuts, whereby the tool may be held in place or when loosened may be rotated about its axis to any desired adjustment.

Although my improved device is preferably intended for use on a drill press and to be driven from the drill socket, I may provide additional or substitute means whereby the shaft 14 may be driven from some other source of power. Merely as an example, I 40 have shown the standard provided with a bracket 34 carrying a shaft 35 on which is secured a drive pulley 36 adapted to receive a belt. The shafts 35 and 14 are parallel and may be connected to be driven at any desired relative speeds by appropriately sized gears 37 and 38.

In order that the work may be properly mounted and moved in respect to the tool, I 50 provide a work table 40 which is capable of adjustment in three directions. The table is shown as being pivotally mounted upon a slide 41, this pivotal mounting including a transverse pivot bolt 42 at one end and slotted flanges 43 at the opposite end. Bolts 55 44 carried by the slide 41 project through the slots and the slots are curved with the pivot 42 as a center. The end of the table 40, opposite to the pivot, may be raised or lowered and clamping nuts on the bolts 44 60 tightened to hold the table at the desired inclination to the horizontal. The slide 41 is mounted to move transversely of a slide 45 and the slide 45 is mounted to move back and forth on the base 10 thus the work on

the table 40 may be moved forwardly or 65 backwardly and laterally in either direction in respect to the tool. Suitable means may be provided for giving to the slides 41 and 45 the desired adjustment. As shown, the lower slide 45 carries a screw bolt 46 with 70 an operating handle 47 and is threaded through an upstanding lug 48 on the base. The slide 41 carries a transverse screw bolt 49 with an operating handle 50 and this is threaded through an upstanding lug 51 carried by the slide 45. By turning the handles 47 and 50 the table 40 may be moved to bring the work to the desired initial position and the work may then be slowly fed in a suitable direction while the tool is operated 80 thereon. The table may have the ordinary means for facilitating the attachment of the work thereto. As shown it has a series of undercut grooves 52 in the upper side thereof. 85

Having thus described my invention what I claim as new and desire to secure by Letters Patent is:

1. A device for slotting or performing other similar machining operations including a base adapted to be secured to a drill press table, a vertical shaft adapted for attachment to and to be driven by a drill press spindle, a vertically movable tool carrier and connections between said shaft and said carrier for reciprocating the latter. 90

2. A device for performing slotting or other similar machining operations including a base adapted to be secured to a drill press table, a work support carried by said base and adjustable horizontally in respect to the latter, a standard carried by said base, a tool carrier having vertical guided connection to said standard and means for reciprocating said tool carrier including a vertical shaft adapted for attachment to the spindle of the drill press. 100

3. An attachment for a drill press including a base adapted to be secured to the drill press table, a standard carried by said base, a vertically movable tool carrier mounted on said standard, a shaft adapted to be attached to the drill press spindle, a horizontal shaft driven from the first mentioned shaft and a pitman connecting said horizontal shaft tool 110 carrier. 115

4. A device of the class described including a base, a standard carried thereby and having a plurality of sections secured together for relative vertical adjustment, a laterally extending arm carried by the upper section and a tool carrier and operating means for the latter carried by said arm. 120

5. A device of the class described including a base, a standard having a laterally extending arm, the body portion of said standard being formed of a plurality of sections secured together for relative vertical adjust- 125

ment, a horizontal shaft carried by said arm, a tool carrier, a vertical guide for the latter intersecting the projection of the axis of said shaft, but spaced from the end of said shaft, 5 eccentric driving conectors between said shaft and said tool carrier and means for rotating said shaft.

6. A device of the class described including a base, a slide movable horizontally 10 thereon in one direction, a second slide movable horizontally on the first mentioned slide and in a direction at right angles to the direction of movement of the latter, a work table secured to said second mentioned 15 slide and tilttable about a horizontal axis, a standard carried by said base and a verti-

cally disposed reciprocating tool carrier mounted on said standard.

7. A device of the class described including a base, a standard carried thereby and 20 having a laterally extending arm, a horizontal shaft carried by said arm, a vertical tool carrier guided by said arm, driving connections between said shaft and said tool carrier, a tool and means for securing said tool 25 to said carrier, and permitting the rotation of the tool carrier about the vertical axis of the tool.

Signed at New York city in the county of New York and State of New York this 7th 30 day of November A. D. 1919.

ERNEST J. ALLEN.
